CLAIM

The ornamental design for a hockey stick, as shown and described.

DESCRIPTION

FIG. 1 is a top perspective view of an embodiment of a hockey stick showing a new design;

FIG. 2 is a bottom perspective view thereof;

FIG. 3 is a side view thereof, the undisclosed opposite side being identical; and,

FIG. 4 is an edge view thereof, the undisclosed opposite side being identical.

The area within the solid and dot-dash-dot lines forms the claimed design. The area within the broken lines is environmental and forms no part of the claimed invention.
